UNITED STATES PATENT OFFICE.

GEORGE P. FINNIGAN, OF PHILADELPHIA, PENNSYLVANIA, ASSIGNOR TO GEORGE A. HOLDEN, OF NEW YORK, N. Y.

SYSTEM OF AUTOMATIC TRAIN CONTROL.

1,299,446.

Specification of Letters Patent.

Patented Apr. 8, 1919.

Continuation of application Serial No. 574,426, filed July 29, 1910. This application filed February 9, 1915. Serial No. 6,990.

To all whom it may concern:

Be it known that I, GEORGE P. FINNIGAN, a citizen of the United States, residing in the city of Philadelphia, county of Philadelphia, and State of Pennsylvania, have invented a new and useful System of Automatic Train Control, of which the following is a specification.

My invention relates to a system for automatically reducing the speed of or bringing to a stop a railway car or train or other vehicle in case it should pass a predetermined point in its path of travel at a speed greater than a predetermined speed.

And my invention relates to a system for automatically giving indications or signals on a moving train or vehicle in response to traffic conditions on its path of travel; or, reversely, giving indications or signals along the path of travel in response to means movable with the vehicle.

To these ends I employ in the path of travel of the train or vehicle means for producing a magnetic flux which shall indirectly influence a train or vehicle circuit which contains suitable translating means for controlling the speed of the train or vehicle and for displaying or giving suitable signals. The train or vehicle circuit is preferably a permanently closed one having connected therein a source of energy and a translating device which may be means for differentiating between positive and negative electro-motive-force waves induced in the train or vehicle circuit.

My invention resides further in a system such as described and involving a train circuit of the character described in association with a further coöperating inductively affected vehicle or train circuit.

A further feature of my invention comprises employment of a permanent magnet, as distinguished from an electro-magnet, for inductively influencing a train or vehicle circuit; a permanent magnet is of peculiar and great value in a system of train control because it is infallible and always operative for producing a magnetic field for desired purposes irrespective of track and weather conditions, and is proof against derangement such as may occur with an electro-magnet whose circuit may be improperly or accidentally broken or whose exciting source of energy may become depleted or otherwise

inoperative. I believe I am the first to appreciate and perceive the decided advantages, in these relations, of a permanent magnet, and the first to apply the same.

And my invention resides further and broadly in the employment of an electro-magnet in association with a permanent magnet for inductively controlling or affecting a train or vehicle circuit; and specifically in such relation that normal energization of the electro-magnet reflects a condition of safety of the vehicle path, and its deenergization, either due to derangement or accident or pursuant to the mode of operation of the system, reflects a condition of danger, the associated permanent and electro-magnets in the first or normal case producing no effect upon the vehicle other than a signal or indication, while in the second case when the electro-magnet is deenergized the permanent magnet, from its infallibility, insures another effect upon the vehicle or train circuit, such as the application of brakes.

My invention resides in further matters and features hereinafter described.

For an illustration of some of the forms my invention may take, reference is to be had in the accompanying drawings, in which:

Figure 1 is a diagrammatic view of a railway track with its associated track circuits and vehicle circuits influencing magnets.

Fig. 2 is a vertical elevational view of vehicle controlling means together with a diagrammatic illustration of coöperating circuits.

Fig. 3 is a diagrammatic and graphic illustration of the track magnets and the flux and electro-motive-force effects produced thereby when a vehicle passes.

Fig. 4 is a fragmentary view illustrating the vehicle control apparatus of Fig. 2 in its normal position.

Fig. 5 is a diagrammatic view illustrating a railway track divided into blocks and provided with track magnets involving the principle of Fig. 1.

Fig. 6 is a fragmentary diagrammatic view illustrating an arrangement of relay for responding to decrease in current.

Referring to Fig. 1, each of the two rails of a railway track is divided into sections or blocks by the insulation *a*, the rails A, A'

- constituting one block, and the rails A^2 , A^3 representing a neighboring block.
- Across the rails A , A' is connected the source of energy C , such as a battery, at one 5 end of said block. At the other end of said block the rail A is connected through conductor e with one terminal of the winding B^2 of an electro-magnet B having the core B^1 of two parts insulated from each other 10 and joined respectively to the rails A^2 and A^3 , the insulation being for the purpose of preventing electrical connection of said rails through the magnet core. The other terminal of the coil or winding B^2 connects 15 through the winding G^1 of a relay and the resistance e' with the end of rail A' . In consequence there is normally a closed track circuit including the source of energy C and the coil B^2 which thus normally energizes 20 the electro-magnet B . As to traffic in the direction of the arrow X it will be noted that the electro-magnet B is traversed in advance of the left hand block comprising rails A and A' , though its winding is included 25 in the track circuit of that block. To the left of the electro-magnet B , and therefore encountered after the electro-magnet B with traffic in direction of arrow X is the permanent magnet H connecting with 30 the opposite rails A^2 and A^3 and provided with insulation for preventing short circuit of said rails as in the case of the electro-magnet B . Traversed in advance of entrance into the block comprising the rails 35 A^2 , A^3 with traffic in the direction of the arrow Y is a second electro-magnet D having the coil D^2 and core D^1 insulated for preventing short circuit of rails A and A' , the coil D^2 being connected in a normally closed 40 track circuit including the conductor f , rail A^3 , source of current or battery E , rail A^2 , winding G of a relay and resistance f' . The permanent magnet H is encountered after 45 the electro-magnet D with traffic in the direction of the arrow Y . The relays G and G^1 are thus in normally closed circuits and serve to control any suitable signaling apparatus in the manner hereinafter described. The train or vehicle has thereon apparatus 50 of the character illustrated in Figs. 2 and 4, Fig. 2, showing the conditions and relations at the time a vehicle has passed over one of the magnets, as B , and Fig. 4 the normal position of the control apparatus.
- I' , I' represent two car wheels and their usual connecting axle I^2 , all usually of iron or steel or other magnetizable material. Carried by the vehicle are the wheel coils J , J' loosely enveloping the wheels between 55 their axle and their treads upon the rails. A second set of wheel coils J' , J' similarly envelop the wheels. The coils J , J' are connected in series with each other for cumulative effect in the vehicle circuit I which is 60 permanently closed and includes the source 65 of current K , such as a battery, the electro-magnet windings L and M and the signaling device or electric incandescent lamp W . The second vehicle circuit T' includes the coils J' , J' connected in series for cumulative effect, such circuit including the winding of electro-magnet T .
- The electro-magnet L is supported upon a suitable bracket or frame L^2 to whose part l' there is pivoted at l the arm or lever L' to 70 which is secured the armature L^3 of the electro-magnet L . Pivoted at n on the lever L' is the detent N having the tail or extension Q' . Lug or detent o on the hammer plunger O normally engaged the detent N , holding 75 the member O in its elevated position, as illustrated. The hammer member O has a loose fit within the cylinder O^1 in which it is guided for vertical movement. Through the head o^2 of the cylinder O^1 extends the handle rod O^2 connected to the hammer O , such protruding handle O^2 serving for manual operation of the member O . The member O may be pointed at its lower end as indicated, and in the path of travel of this pointed 80 member is disposed the frangible disk or plate P' , as of glass, forming a closure between the interior of the cylinder O^1 and the connection P communicating with the train pipe of the air brake system of the vehicle. 85 Above the member P' the cylinder O^1 has a port o^1 communicating with the atmosphere. 90
- The electro-magnet M is supported by the frame L^2 and has the armature m attached to the vertically movable rod Q carrying at 95 its upper end a member q adapted to intervene between the tail Q' of detent N and the stop q' on the frame L^2 . The rod Q is guided in its vertical movement through holes in the frame L^2 and in the arm r' . 100 The rod Q is provided with a shoulder r adapted to engage on the top of the dog R pivoted to the arm r' and having the cam slot s in which engages the pin s' carried by the armature lever S of the electro-magnet T . The electro-magnet T is sluggish or slow acting so that its armature will be attracted at a time lagging appreciably after the impulses traversing the winding of the electro-magnet T . This may be accomplished in various ways well known in the 105 art.
- In Fig. 1 there are indicated at b and c rail sections or inserts of manganese steel or any other suitable material which like manganese steel is a non-magnetic or substantially non-magnetic, the sections d at the heads of the magnets B and D being magnetic material, as ordinary iron or steel rails like A , A' , A^2 and A^3 . These inserts 110 b and c therefore confine the magnetic paths of the electro-magnets B and D and are utilizable whenever such end is desired, though it will be understood that my invention is not limited to their use. It will 115 120 125 130

be understood however, that these parts *b* and *c* do not interrupt the electrical conductivity of the rails and therefore in no way affect the track circuits.

5 The operation is as follows:

Assuming a vehicle to be in the right hand block, Fig. 1, that is, running upon the rails *A*² and *A'* in the direction of the arrow *X*, if there is no vehicle or train in the left hand block comprising the rails *A* and *A'* the electro-magnet *B* will be energized. The ampere turns of the coil *B*² of the electro-magnet *B* preponderate over the ampere turns of the vehicle wheel coils *J*, *J'*, Fig. 2, through which current is normally passing from the source *K*. That is, the vehicle circuit *I* tends to magnetize the wheels *I*', *I*'², and, for example, in such direction that the left hand wheel *I*', Fig. 2, where it contacts the rail *A*² is a south pole, indicated by *s. p.*, and the tread of the other wheel a north pole, indicated by *n. p.*; and the left hand end of the electro-magnet *B*, Fig. 2, similarly produces a south pole, also marked *s. p.*, and the right end a north pole, marked *n. p.* As the electro-magnet *B* is the stronger and when the wheels *I*', *I*'² are directly over it the electro-magnet sets up a flux through its core and through the rails and wheels and axle in opposition to the flux which the ampere turns of the circuit *I* tend to set up. The result is that the normal flux through the wheels and axle of the vehicle are not only overcome, but actually reversed, with the result that there is induced in the vehicle circuit *I* an electro-motive-force wave, for example a positive wave, which operates cumulatively with the electro-motive force of the source *K*, to momentarily increase the electro-motive-force operative in the circuit *I*, with resultant increase of the current above normal strength. The magnetism normally produced by the electro-magnet *L* is sufficient to hold the lever *L'* in the position indicated in Fig. 4. Normally the magnetism produced by the magnet *M* is insufficient to lift its armature *m* and the attached member *q*. Upon occurrence of the increased current due to passage over the track electro-magnet *B* the electro-magnets *L* and *M* are energized to a degree above normal, with the result that the electro-magnet *L* continues to hold its armature *L*³ and the attached lever *L'*, but magnet *M* is now excited to such degree that it attracts its armature *m* and lifts the rod *Q*, bringing the member *q* into the position illustrated in Fig. 2 between the tail *Q'* and the stop *q'*, preventing so long as this position is held the release of lever *L'*. Simultaneously with the induction of an electro-motive-force wave in the circuit *I* there is an impulse of current induced in the circuit *T'* through the coils *J*', *J'*, energizing the slug-

gish magnet *T* which attracts its armature lever *S* upwardly after armature *m* has been attracted and shifts the dog *R* from its position shown in Fig. 4 into the path of the shoulder *r* which engages the top of the dog *R*, as shown in Fig. 2, so that when magnet *M* is weakened the member *Q* is prevented from falling by dog *R*, and later, as magnet *T* releases member *S*, dog *R* is withdrawn from the path of shoulder *r*. The member *q* is still prevented from falling while current in circuit *I* is below normal strength during the succeeding impulse induced in opposite direction by a pinching action taking place between members *Q'* and *q'*, because of weakening of magnet *L*, until the current in the circuit *I* returns to normal strength, whereupon magnet *L* continues to attract its armature *L*³, which attraction now supplants the holding effect of member *q* upon lever *L'*. Upon the return of current in circuit *I* to normal strength the member *q* is released, because with current at normal strength in the circuit *I* magnet *M* cannot hold its armature *m* attracted, and the member *q* falls to its normal position shown in Fig. 4. After the return of the current in circuit *I* to normal strength, magnet *T* receives a second impulse with no effect upon the member *q*. The magnet *T* responds to both positive and negative impulses induced in its circuit *T'*.

In other words, when traffic conditions are normal or safe, the electro-magnet *B* remains energized, and in passing over the magnets *B* and *H* in succession, there is first induced in the vehicle circuit *I* an electro-motive-force assisting the source *K* to produce an increased current, which is followed by an electro-motive-force wave in opposite direction decreasing the current below normal value, but, due to the sluggishness of the magnet *T*, the vehicle passes the permanent magnet *H* without release of the armature lever *L'*.

If, however, there is a vehicle in the left hand block, comprising the rails *A* and *A'*, the source of current *C* will be short circuited through the wheels and axle of that vehicle with the result that the electro-magnet *B* will be deenergized. Then when the vehicle of the right hand block reaches the magnet *B* there will be no flux passed by magnet *B* through the wheel coils. Upon reaching the permanent magnet *H*, a flux will be induced through the wheel coils in the same direction as produced by the ampere turns of the vehicle circuit resulting in a negative wave of electro-motive-force which opposes the source *K*, with the result that the strength of the current in the vehicle circuit *I* is substantially reduced, with the result that magnet *L* is deenergized to such degree that it releases its armature *L*³, the magnet *M* being unresponsive, due to

the fact that the current is even below normal strength, and consequently the lever L' rises upwardly upon its pivot l , withdrawing the detent N from beneath the lug 5 o , with the result that the hammer O drops and breaks the disk P' , whereupon the pressure in the train pipe of the air brake system operates upon the lower end of plunger O , giving the same an upward impulse, causing 10 it to uncover part o' putting the train pipe into communication with the atmosphere, and accordingly the vehicle brakes are applied to reduce the speed of the vehicle, or to bring it to a stop. As the train 15 pipe pressure falls plunger O settles to normal position where it is held by detent o . In such case the electro-magnet T performs no function, and though energized when the circuit T' is inductively affected through 20 the wheel coils J', J' , it produces no effect because the rod Q has not been raised by the magnet M .

It will accordingly be seen that the apparatus differentiates between the positive and 25 negative impulses induced in the vehicle circuit, with the result that if an impulse of one polarity, for example positive, is first induced, the vehicle control apparatus is not affected, but if an impulse of opposite 30 polarity is first induced the vehicle control apparatus responds.

The operation for traffic in opposite direction is the same as that above described for a vehicle or train in the left hand block 35 which will first encounter the electro-magnet D , which is either energized or deenergized, according as the right hand block is not or is occupied, and thereafter encounters the permanent magnet H .

40 In Fig. 3 the curve represents graphically the change in the magnetic flux through the wheel coils for traffic from left toward the right over electro-magnet D and permanent magnet H . E is the corresponding curve of electro-motive-forces induced in the vehicle circuit. From this it will be seen that first a positive, for example, electro-motive-force wave x is induced in the vehicle circuit followed by a negative wave 45 y . It will be understood that these curves are illustrative merely, and that it is appreciated that the actual form of electro-motive-force waves may be distorted from that illustrated.

50 In Fig. 5 is illustrated a system similar to that of Fig. 1, but for traffic in one direction only. Here like reference characters represent like parts of Fig. 1, and the operation of the system of Fig. 5 will be understood to be that described in connection with Fig. 1 for traffic in the direction of the arrow X . In this figure, however, one more complete block is shown comprising the rails A^4 and A^5 .

55 While in the foregoing description it has

been assumed that the permanent and electro-magnets in the path of travel of the train or vehicle are capable of producing a flux through the vehicle circuit coils stronger than and in opposition to the flux which the vehicle circuit itself tends to set up, the relation may be otherwise. For example, the ampere turns produced by the wheel coils J, J in circuit I may be so great that in passing over the core of an electro-magnet 70 B in the trackway when such electro-magnet has been deenergized, there will be set up by induction in the vehicle circuit an electro-motive-force wave which will be sufficient in its effect to cause the control mechanism 75 to operate. In such case the permanent magnet may be omitted. With the electro-magnet B energized, movement of the vehicle thereover will be accompanied by the induction in the circuit I , Fig. 2, of an electro-motive-force in the same direction as the electro-motive-force of the battery K , causing, for such initial impulse, a strengthening of the current in the circuit I above 80 normal, the succeeding impulse due to departure of the vehicle from the magnet B being in opposite direction and causing the weakening of the current in the circuit I . The result is that there will be no response. 85 as in the case hereinbefore described. If, however, the electro-magnet B is deenergized, the movement of the vehicle to the magnet B will be accompanied by the induction in the circuit I of an electro-motive-force opposing the electro-motive-force of the battery K , with the result that such initial impulse causes a weakening of the current in the circuit I below normal, with resultant response of the apparatus, as in 90 the case hereinbefore described. 95

100 It will be understood that upon the increase of current in the vehicle circuit I above normal the lamp W will momentarily glow more brightly and thus serve to give a visual signal that an electro-magnet has 105 been passed over which is energized, and so indicating a condition of safety.

110 And it will be understood that any suitable audible or visual signals may be provided on the vehicle and which shall respond to the currents induced in either of the vehicle circuits.

115 By employing a system of normally closed track circuits for controlling the track electro-magnets, any failure of such circuit, as by broken rail, depleted battery, or other cause, the vehicle control mechanism will respond, due to resultant deenergization of the track electro-magnet.

120 And by preference the vehicle circuit is 125 permanently closed and includes a source of energy. And upon any failure in such vehicle circuit, as by broken circuit, depletion of battery or other cause, the same will be indicated by signal or response of vehicle 130

control mechanism as in the case of danger condition on the trackway.

While the inductive effects have hereinbefore been described as occurring in the vehicle circuit or circuits it will be noted that in passing over an electro-magnet B in the trackway an inductive effect or variation of current in the circuit of the electro-magnet winding B² also occurs, which may be availed of to produce any suitable signal or control along the trackway. Thus when the ampere turns produced by the wheel coils J, J in the vehicle circuit I are so great that they can cause a substantial change in the magnetic flux in the core B¹ of an electro-track magnet B, there will be induced in the circuit of the winding B² an electro-motive-force which will transiently alter the current produced in such circuit by its energizing battery or source of current. This alteration of the normal current will be responded to by the relay, as G¹, by a movement of its core, which movement may control any signaling, indicating or other means. The electro-motive-force so induced in the circuit of the winding B² will comprise waves of opposite polarities, so that a wave of one polarity will assist the energizing battery, as C, while the other will oppose it. In other words one of the electro-motive-force waves will cause an increase in current while the other will cause a decrease in current, and either the increase or decrease in current will cause response of the relay, as G¹, to control the production of a signal, indication or control. In the example illustrated the relay normally energized by the battery will respond to the increase of current due to induction to lift the contact 2 from contacts 3 and 4 to break the circuit whose ends are the conductors 5 and 6 connected to contacts 3 and 4. There is no response to decrease in current, and there is therefore a selective action.

And a similar effect can be produced in the circuit of the winding B² without the employment of a vehicle circuit. A pair of wheels and their axle passing over the normally energized electro-magnet B will cause a variation in the magnetic flux, which change in flux will be reflected by a change in current strength in the circuit B², and this change of current may be similarly used for producing an indication, signal or control.

And where a vehicle circuit is employed as above described with a source of current therein, the circuit of the electro-magnet coil B² may be a closed circuit including a translating device and no source of energy. In which case the induced current alone will produce an indication, signal or control.

This application is a continuation of my application Serial Number 574,426, filed 65 July 29, 1910.

What I claim is:

1. In combination, a car, controlling devices located thereon, and power operated actuating means located adjacent to the path of the car, adapted to operate the controlling devices when the power is not being applied and not to operate them when it is applied, comprising a permanent magnet and an electro-magnet, said magnets being independent of each other. 70

2. In combination, a car, controlling devices located thereon, power operated actuating means located adjacent to the path of the car, adapted to operate the controlling devices when the power is not being applied and not to operate them when it is applied, comprising a permanent magnet and an electro-magnet, said magnets being independent of each other, the controlling devices having a magnetically actuated member. 80

3. In combination, a car, controlling devices located thereon, power operated actuating means located adjacent to the path of the car, adapted to operate the controlling devices when the power is not being applied and not to operate them when it is applied, comprising a permanent magnet and an electro-magnet, said magnets being independent of each other, the controlling devices having a magnetically actuated lever. 90

4. A train control system comprising a permanently magnetized inductor, a co-operative inductance upon the moving train, mechanism actuated by the current generated in said inductance, and an electro-inductive means of communication to the train for controlling said mechanism. 100

5. A system for automatically inductively controlling or producing an indication upon a vehicle comprising the combination with a moving vehicle, of a permanent magnet disposed in the path of travel of said vehicle, a closed vehicle circuit, a source of current and an electro-magnetic winding normally energized by said source of current included in said circuit, and a member normally held by said electro-magnetic winding, said electro-magnetic winding releasing said member in response to inductive effects produced in 110 said circuit by said permanent magnet.

6. A system for automatically inductively controlling a vehicle comprising the combination with a moving vehicle, of a brake controlling member, a vehicle circuit, a source of current and an electro-magnetic winding included in said circuit, said winding normally energized by said source of current to restrain said brake controlling member, and a permanent magnet disposed 120 in the path of travel of said vehicle for inductively influencing said vehicle circuit to release said member.

7. The combination with a plurality of magnets, of a circuit movable with respect 130

thereto and differently influenced inductively thereby, said magnets producing magnetic fluxes in opposite directions with respect to said circuit, and a translating device controlled by said circuit and selectively responsive to different inductive effects in said circuit produced by different of said magnets.

8. The combination with a permanent and 10 an electro-magnet, of a circuit movable with respect thereto, and inductively influenced thereby, a translating device controlled by said circuit, and means causing different effects upon said translating device 15 when said electro-magnet is energized and deenergized.

9. The combination with a moving vehicle, 20 of a permanent magnet and an electro-magnetic coil disposed in the path of travel of said vehicle, means for energizing said coil, a vehicle circuit, a translating device controlled thereby, said coil when energized preventing response of said translating device to the inductive effect upon said circuit 25 by said permanent magnet.

10. The combination with a moving vehicle, of a permanent magnet and an electro-magnetic coil disposed in the path of travel of said vehicle, a vehicle circuit, a translating 30 device controlled thereby, means for energizing said electro-magnetic coil, said permanent magnet and said coil being so disposed that their magneto-motive-forces are opposed with respect to said circuit.

35 11. The combination with a moving vehicle, of a permanent magnet and an electro-magnetic coil disposed in the path of travel of said vehicle, a vehicle circuit, a translating device controlled thereby, means for energizing said coil, said permanent magnet and said coil being so disposed that their magneto-motive-forces are opposed with respect to said circuit, said translating device being unresponsive to said coil and permanent 45 magnet when said coil is energized.

12. The combination with a moving vehicle, of a permanent magnet and an electro-magnetic coil disposed in the path of travel of said vehicle, a vehicle circuit, a translating 50 device controlled thereby, means for energizing said coil, said permanent magnet and said coil being so disposed that their magneto-motive-forces are opposed in their effects upon said circuit, said translating device being unresponsive to said coil and permanent magnet when said coil is energized and responsive to said permanent magnet when said coil is deenergized.

60 13. The combination with a moving vehicle, of a permanent magnet and an electro-magnetic coil disposed in the path of travel of said vehicle, a vehicle circuit, a source of energy in said circuit, electro-magnetic controlling means normally energized by said 65 source, and means for energizing said elec-

tro-magnetic coil, the magneto-motive-forces of said permanent magnet and coil being opposed with respect to said vehicle circuit, said electro-magnetic means being deenergized by inductive effects produced in said circuit by said permanent magnet when said electro-magnetic coil is deenergized.

70 14. The combination with a moving vehicle, of a vehicle circuit, a source of energy and electro-magnetic means normally energized thereby connected in said circuit, a brake controlling member normally held by said electro-magnetic means, a permanent magnet disposed in the path of travel of said vehicle for inductively influencing said circuit to cause deenergization of said electro-magnetic means to release said brake controlling member, an electro-magnetic coil in the path of travel of said vehicle, and means for energizing said coil to prevent deenergization of said electro-magnetic means by said permanent magnet.

75 15. The combination with a moving vehicle, a vehicle circuit, means disposed in the path of travel of said vehicle for inductively affecting said circuit, a translating device controlled by said circuit, a second vehicle circuit inductively affected by said means, and means controlled by said second circuit for controlling said translating device.

80 16. The combination with a moving vehicle, of a plurality of circuits thereon, a translating device controlled by one of said circuits, means disposed in the path of travel of said vehicle for inductively affecting said vehicle circuits, and means controlled by a second of said vehicle circuits for preventing response of said translating device to electro-motive-force induced in said first circuit in a predetermined direction.

85 105 17. The combination with a moving vehicle, of a plurality of circuits thereon, a translating device controlled by one of said circuits, means disposed in the path of travel of said vehicle for inductively affecting said vehicle circuits, and means controlled by a second of said vehicle circuits for allowing response of said translating device to electro-motive-force of predetermined direction only when succeeding electro-motive-force of opposite direction induced in said vehicle circuit.

110 18. The combination with a moving vehicle, of a plurality of circuits thereon, one of said circuits controlling a translating device, a second of said circuits controlling means controlling said translating device, a plurality of track magnets passed in succession by said vehicle and producing in said vehicle circuits overlapping series of positive and negative electro-motive-force waves, said translating device and said controlling means constituting means selectively responsive to an electro-motive-force wave of one sign when occurring in a predetermined po-

sition in a series of induced positive and negative electro-motive-force waves.

19. The combination with a moving vehicle, of a plurality of vehicle circuits, a source of energy and electro-magnetic means normally energized thereby included in one of said circuits, a member normally restrained by said electro-magnetic means, means controlled by a second of said circuits 10 for preventing release of said member, and means disposed in the path of travel of said vehicle for inductively influencing said vehicle circuits.

20. The combination with a moving vehicle, of brake controlling mechanism thereon, a normally closed vehicle circuit, a source of current in said circuit, an electro-magnet in said circuit, a second vehicle circuit, a magnet in said second circuit, said magnets 20 co-operatively controlling said brake controlling mechanism, and means in the path of travel of said vehicle inductively influencing said vehicle circuits.

21. The combination with a moving vehicle, of a normally closed circuit thereon, an electro-magnet in said circuit, vehicle controlling means controlled by said magnet, means disposed in the path of travel of said vehicle for successively inducing in said circuit electro-motive-forces in opposite directions, and means for preventing said magnet effecting a control of said train controlling means by an induced electro-motive-force in one direction.

35 22. The combination with track rails, of an electro-magnet whose core bridges said rails, a permanent magnet bridging said rails adjacent said electro-magnet, a vehicle, a pair of wheels and their connecting axle 40 carried thereby, said wheels rolling in contact with said rails and forming a magnetic path with said rails, a closed vehicle circuit inductively affected by said magnets, a source of current in said circuit, and a translating device responsive to variations of current in said vehicle circuit.

23. The combination with a plurality of block sections, of a permanent magnet and an electro-magnetic coil for each block section, a closed track circuit for each block section, each track circuit including a source of energy and one of said electro-magnetic coils, a vehicle movable over said track sections, and a vehicle circuit inductively influenced by said permanent magnets and said electro-magnetic coils.

55 24. The combination with a plurality of block sections, of a permanent magnet and an electro-magnet disposed in advance of the entrance of each block section, a closed track circuit for each block section, each track circuit including a source of energy and the winding of one of said electro-magnets, and a vehicle circuit inductively influenced 60 by said permanent and electro-magnets.

25. The combination with a vehicle, of a rail over which said vehicle is movable, said rail having magnetizable and non-magnetic sections, a magnetizable member movable with said vehicle in co-operative relation with 70 said rail, means for producing a magnetic flux in said member and a magnetizable rail section, and a translating device responsive to magnetic changes resulting from passage of said member from one of said sections to 75 another.

26. In an automatic train stop and signal system, a normally closed train circuit including an electro-magnet, train controlling means controlled by said magnet, means including the track for successively inducing electro-motive-forces in opposite directions in said train circuit, and means controlled by the electro-motive-force induced in one direction for preventing the magnet operating the train controlling means by the induced electro-motive-force in the other direction.

27. In an automatic system of train control, a normally closed track circuit including rails each provided with non-magnetic sections positioned at the respective sides of a magnetic rail section, and a magnet connected to said magnetic rail section.

28. In a railway signaling system, a closed track circuit, a coil in said track circuit, a circuit on a moving vehicle, means for producing uni-directional magnetic flux threading said coil and said vehicle circuit when adjacent to each other, movement of said circuit with respect to said coil generating electro-motive-force in said track circuit, and signaling means controlled by said electro-motive-force.

29. In a railway signaling system, a normally closed track circuit, an electro-magnet disposed in the track and having a winding included in said circuit, a closed circuit on a moving vehicle, a translating device included in said vehicle circuit, relative movement between said vehicle circuit and said magnet generating electro-motive-forces in said first named circuit and in said vehicle circuit, said translating device in said vehicle circuit being controlled by electro-motive-force induced in said vehicle circuit, and track signal controlling means controlled by the electro-motive-force induced in said first named circuit.

30. In combination two track rails, a core 120 across the track rails and connected therewith; a coil surrounding said core; a circuit for said coil; a permanent magnet also connected with the track rails and adjacent said core; a vehicle; a pair of wheels and their connecting axle carried thereby and said wheels having rolling contact with the track rails; a coil carried by the vehicle which is cut by the fluxes in said magnet; 130

a closed circuit including said coil; a source of current for said circuit; and a translating device affected by variations of current in said closed circuit.

- 5 31. In combination a permanent line of way; an electro-magnet having its core magnetically connected with a rail of said permanent line of way; means for controlling the energization and deenergization of the 70
10 electro-magnet; a vehicle; a wheel carried by the vehicle and having rolling contact with a rail with which the core is connected; a coil; a circuit including said coil; a source of current for said circuit; a translating 75
15 device affected by variations of current in said circuit; and means associated with the translating device for preventing its operation when the vehicle passes over and beyond an energized electro-magnet, but for
20 permitting an operation by it when it passes over a deenergized electro-magnet.

32. In combination a permanent line of way; an electro-magnet having its core magnetically connected with a rail of said permanent line of way; a permanent magnet associated with said electro-magnet and magnetically connected with the same rail; means for controlling the energization and deenergization of the electro-magnet; a vehicle; a wheel carried by the vehicle and having rolling contact with the rail to which the said core and permanent magnet are connected; a coil; a circuit including said coil; a source of current for said circuit; a translating device affected by variations of current in said circuit; and means associated with the translating device for preventing its operation when the vehicle passes over and beyond an energized electro-magnet, but for 90
30 permitting an operation of it when it passes over a deenergized electro-magnet.

33. In combination two track rails; an electro-magnet having its core magnetically connected with the track rails; a permanent magnet associated with said electro-magnet and magnetically connected with the track rails; means for controlling the energization and deenergization of the electro-magnet; a vehicle, the wheels of which have rolling 95
45 contact with the track rails; two coils; closed circuits carried by the vehicle and including said coils; a source of current in one of said circuits; a translating device controlled by said circuits and adapted not to
50 be operated when it passes over an energized electro-magnet but to be operated by the permanent magnet when passing over a deenergized electro-magnet.

34. The combination with the track rails 100
60 of a railway; a track electro-magnet having its core magnetically connected with the track rails; means for controlling the energization and deenergization of the track electro-magnet; a vehicle traveling along the 105
65 railway; a closed circuit carried by the ve-

hicle; a source of current for said circuit; a translating device energized by the current from said source to perform one function; and means carried by the vehicle for preventing the translating device performing a different function when a car passes over and away from an energized magnet and allowing it to perform a different function when it passes over a deenergized track electro-magnet.

35. The combination with the track rails of a railway; a track electro-magnet having its core magnetically connected with the track rails; means for controlling the energization and deenergization of the track 80
85 electro-magnet; a permanent magnet adjacent the track electro-magnet and magnetically connected with the track rails; a vehicle traveling along the railway; a closed circuit carried by the vehicle; a source of current for said closed circuit; a translating device also in said circuit and energized by the current from said source to perform one function; and means carried by the vehicle for preventing the translating device changing its function when a vehicle passes over and away from an energized track electro-magnet and an associated permanent magnet, but for causing said translating device to perform a different function when it 90
95 passes over a deenergized track electro-magnet and the associated permanent magnet.

36. In a system of the character described, the combination with a moving vehicle, of a plurality of magnets disposed in its path 100
105 of travel, a track circuit, one of said magnets controlled by said track circuit and another of said magnets being independent of control by said track circuit, a vehicle circuit inductively influenced by said magnets, and a translating device in said vehicle circuit.

37. In a system of the character described, the combination with a moving vehicle, of a plurality of magnets disposed in its path of travel, a track circuit, one of said magnets controlled by said track circuit and another of said magnets being independent of control by said track circuit, a vehicle circuit inductively influenced by said magnets, and a translating device in said circuit selectively responsive to different inductive effects produced in said circuit by said different magnets.

38. In a system of the character described, the combination with a moving vehicle, of a 120
125 plurality of magnets disposed in its path of travel, a track circuit, one of said magnets controlled by said track circuit and another of said magnets being independent of control by said track circuit, a vehicle circuit inductively influenced by said magnets, and a translating device in said circuit, said magnets being so disposed that their magneto-motive-forces are opposed with respect to said vehicle circuit.

39. In a system of the character described, the combination with a moving vehicle, of a plurality of magnets disposed in the path of travel of said vehicle, a circuit, a winding of one of said magnets included in said circuit and controlled thereby, another of said magnets continuously producing magnetic flux, a vehicle circuit, a translating device controlled by said vehicle circuit, 10 said magnet coil when energized preventing response of said translating device to the inductive effect upon said vehicle circuit by said other magnet.

40. In a system of the character described, 15 the combination with a moving vehicle, of a vehicle circuit, means comprising opposed sources of magneto-motive-force disposed in the path of travel of said vehicle for inductively affecting said vehicle circuit, 20 means controlling said means for determining the direction of an initial impulse of electro-motive-force induced in said vehicle circuit, and means responsive only to an initial electro-motive-force impulse induced 25 in predetermined direction in said vehicle circuit.

41. In a system of the character described, the combination with a moving vehicle, of a vehicle circuit, means disposed in the path 30 of travel of said vehicle for inductively influencing said circuit, means controlling said means to determine the direction of an initial electro-motive-force impulse induced

in said circuit, a magnet in said vehicle circuit, a second magnet subjected to electro-motive-force induced by said first named means, the circuits of said magnets having different time constants, and translating means controlled by said magnets, said magnets coöperating to effect said control only 35 in response to an initial impulse of electro-motive-force of predetermined direction. 40

42. The combination with a vehicle traveling along a fixed line of way, a wheel carried thereby, a coil surrounding said wheel, a closed circuit for said coil, a source of electro-motive-force and a translating device also included in said circuit, and a permanent magnet located in the line of way 45 for co-action with the coil and its closed 50 circuit.

43. The combination with a vehicle traveling along a fixed line of way, a coil carried by said vehicle, a closed circuit for said coil, a source of electro-motive-force and a 55 translating device also included in said circuit, and a permanent magnet located in the line of way for co-action with the coil and its closed circuit.

In testimony whereof I have hereunto 60 affixed my signature in the presence of the two subscribing witnesses.

GEORGE P. FINNIGAN.
